UNITED STATES PATENT OFFICE.

JOSEPH HELLER, OF NEW YORK, N. Y.

AERIAL TOY.

Application filed January 10, 1927. Serial No. 160,023.

This invention relates to games and toys and especially such toys as are designed for not only amusement purposes for children, but also to impart to any persons a stimulus 5 for inquiring into the principles of aeronautics, the toy being designed to a large extent for the purpose of inspiring thought and investigation as to the principles or mysteries of the conduct of air upon moving bodies.

Among the objects of the invention is to provide a cheaply constructed and attractive device in the nature of a toy for aerial purposes which may be utilized, among other 15 things, for the carrying of an advertisement and which may be discharged from any elevated position, as from the top or window of a sky scraper building, a kite, or from an airship.

With the foregoing and other objects in view the invention consists in the arrangement and combination of parts hereinafter described and claimed, and while the invention is not restricted to the exact details of 20 construction disclosed or suggested herein, still for the purpose of illustrating a practical embodiment thereof reference is had to the accompanying drawings in which like reference characters designate the same 25 parts in the several views, and in which—

Figure 1 is a face view of one side of my improved toy.

Fig. 2 is a similar view of the other side.

Fig. 3 is a plan view of the blank for the 30 formation of the binder and weight member.

Fig. 4 is a plan view of the blank or pattern for the blade.

Fig. 5 is a plan view of the blank of the 35 stiffener and with indication of the relation thereto of the blade.

Fig. 6 is a transverse section on the line 40 6—6 of Fig. 1.

Fig. 7 is a similar view on the line 7—7 of Fig. 1.

Referring now more specifically to the 45 drawings I show my device as comprising an assemblage of three parts,—a blade 10, a stiffener 11, and a combined weight and binder 12.

The blade is formed from a single ply of 50 thin light sheet material such as onion skin or tissue paper and is provided with a wide point portion 13 remote from the narrower shank portion 14.

The stiffener as shown in Fig. 5 is cut or

stamped from a single ply of sheet material such as a heavier or thicker quality of paper than is used for the blade, the blank consisting of two equal and symmetrical portions foldable one upon the other along a 60 medial bending line 15 and the same comprises two circular or disk portions 16 and two blade portions 17. In the assemblage of the blade and stiffener members, the forward or advancing edge 18 of the blade is 65 applied to one of the halves of the stiffener as shown by dotted lines in Fig. 5 while the shank portion 14 thereof overlaps one of the disks 16. The other half of the stiffener is then folded over, being superposed directly 70 upon the first mentioned half, and the blade and stiffener members are then secured firmly as by glue to one another, constituting the stiffener and blade as a unit. The stiffener, as its name implies, stiffens and 75 re-enforces the leading edge of the blade and holds such portion of the blade substantially flat. The stiffener and the blade constitute a wide smooth substantially flat member upon either side of which may be printed 80 or otherwise placed advertising matter or the like for publicity purposes. The device may be made so cheaply that it is well adapted for free distribution with bread or other commodity, thus insuring a wide range 85 of publicity for the message carried thereby.

The binder is cut or stamped from heavier material such as tin, aluminum, or other thin flat metal and preferably of the design shown in Fig. 3, the same comprising two 90 disk portions 19 and 19^a united to each other along a foldable neck 20, and either of these disks bears preferably two spaced lugs 21 adapted to fold or crimp around the other companion member 19. One of the disks, 95 moreover, as for instance 19^a, is provided with a shank extension 22 which bears at its point a laterally projecting lug 23.

With the lug 23 bent upward at an angle to the plane of the shank 22, the combined 100 stiffener and blade unit above referred to may be inserted between the two disks 19 and 19^a. The leading edge portion 24 of the stiffener will abut against the lug 23, while the disk portion 16 will be received 105 and fit directly between the two disks of the binder. The other disk member 19 will then be brought down firmly upon the disks 16 and the lugs 21 bent or crimped around as shown in Fig. 2. The union at the bending 110

line 20 and the lugs 21 serve to bind the disks of the binder firmly together in flat form and this binding action together with the lug 23 serves to lock or bind the combined stiffener and blade unit in the place indicated. The combined weight and binder, while of thin structure, has a substantial degree of weight as compared with the blade, and the shank 22 thereof carries a substantial degree of stiffness from the binder out along the backbone or leading edge 24 of the stiffener. The portion of the stiffener outward therefrom maintains a certain degree of stiffness, much more than the blade, especially because of the fact that it is formed of two parts gummed firmly together and embraced by a portion of the binder. The trailing and point portion of the blade, being of a single ply of thin stock, is free to flex in practice.

The operation of the toy is as follows: When tossed into the air or dropped from any relatively high point or degree of elevation, for some reason, the scientific explanation for which is not entirely clear to me, instead of the weighted or binder end 12 of the device gravitating directly and sharply to the ground, the toy almost immediately swings into a horizontal plane, probably due to the lack of symmetry thereof on opposite sides of the axis of the blade, and thenceforth the toy gravitates slowly, maintaining its horizontal position, but spins rapidly around a vertical axis somewhere within the disk portion of the weighted binder, the free edge 25 of the blade trailing. Since the device gravitates slowly and in a substantially horizontal position, it comes to rest with the least amount of likelihood of being damaged so that it may be projected into the air repeatedly with results as above stated.

I claim:

1. The herein described aerial toy comprising a combined stiffener and blade, the blade being made of thin stock and the stiffener being made of heavier stock, the blade and stiffener being united in flat form to form a unit having a relatively rigid leading edge and a thin pliable trailing edge, and a combined binder and weight member of disk formation connected to one end of the unit aforesaid and being of flat construction and all in substantially the same plane.

2. A toy as set forth in claim 1 in which the stiffener is formed from two symmetrical parts folded one above the other and with the leading edge of the blade held firmly between them.

3. A device as set forth in claim 1 in which the combined weight and binder member comprises two flat portions mating with each other in the main and between which the shank portion of the blade and stiffener unit is gripped.

4. A construction as set forth in claim 1 in which the combined weight and binder member comprises a flat disk having a relatively rigid extension leading along the leading edge of the stiffener and having means to secure the stiffener thereto.

5. The herein described aerial toy comprising a weight having two substantially symmetrical and concentric disks adapted to be superposed one over the other, one of the disks having lugs to crimp over the periphery of the other for binding them together in flat form, a thin blade having one end projected from and between the disks, and stiffening means extending from the disks along the leading edge of the blade to impart partial stiffness thereto.

In testimony whereof I affix my signature.
JOSEPH HELLER.
